MOTORIZED HANDPIECE

Howard A. Whiteside, New York, N. Y.

Application April 16, 1934, Serial No. 720,839

3 Claims. (Cl. 32—23)

The present invention relates to motorized hand pieces and more particularly to such devices as are suitable for being held in the hand while performing dental or surgical operations or other delicate work.

Surgical and dental engines and similar tools employ a hand piece consisting essentially of a stationary sheath adapted to be held between the thumb and finger tips of one hand and a rotatable shaft carried in the sheath. The outer end of the shaft is connected to a tool and the rear end to a source of power, such as a driving shaft or spindle. The sheath of the hand piece is detachably secured to the bearing device for the driving shaft or spindle. Where the engine is of the belt driven type, the coupling device includes a slip joint and means to carry the pulley for driving the spindle or shaft; and where the engine has the flexible shaft type of drive, the coupling device is connected to the sheath about the flexible shaft. When assembled, these hand pieces and coupling devices form a rigid unit which extends from in front of the finger tips to back of the knuckle so that this rigid unit may be grasped in the hand and manipulated thereby. It was thus necessary to have the hand piece and small diameter part of the coupling at least six inches long.

Suggestions have been advanced by the present applicant and by others for the direct connection of an electric motor to the hand piece or slip joint, and the following patents are representative of such suggestions:

Sargent, 776,204, November 29, 1904; Shelton, 1,201,262, October 17, 1916; Whiteside, 1,189,184, June 16, 1916; Whiteside, 1,587,738, June 8, 1926; Whiteside, 1,836,350, December 15, 1931. Reference to these patents will show that the hand pieces and coupling devices were of such length and diameter that, when held in the hand, the motor was disposed behind the knuckle. To develop adequate torque, the motors were made of considerably larger diameter than the hand piece and coupling, and were made as short as possible to conserve weight and length, and facilitate handling. In these constructions the hand pieces and coupling weigh $\frac{3}{4}$ ounce to 3 ounces and the motors from 4 ounces to 12 ounces, and hence the center of gravity in all such motorized tool units must be in the motor and therefore to the rear of the knuckles.

According to the present invention, the motorized tool unit is designed as an entity for the use to which it is intended. The length of the hand piece and coupling are reduced and the mo-

tor is made of much smaller diameter and longer. The tool units contemplated by the present invention may be grasped between the thumb and fingertips in the usual way and the motor rests on the interdigital space between the thumb and index finger. 5

The rear end of the unit projects a short distance behind the knuckle, but the center of gravity of the unit is near the lower or front end of the motor. Hence, the unit has no tendency to 10 overturn as is present in the motorized tool units having long hand pieces and overhanging motors.

I have also found that these units may be held or gripped much more securely with less effort. Should the operator relax the grip on the former 15 type of unit, the heavy motor would drag the unit out of the hand, causing it to drop. Relaxing the grip on the improved form of construction does not release the unit. It rests in the hand loosely, like a pencil which is not tightly gripped. 20 The motor diameter is larger than the diameter of the usual hand piece and fits into the space between the index finger knuckle and thumb knuckle in such a way as to reduce the amount of rolling or traveling of the unit owing to its 25 tendency to pivot about the gripping point. It is easier for the operator to see around the instrument and work in restricted spaces as there is no large motor body to interfere with vision. Also the tendency of the former type mechanism 30 to cast shadows on the work is almost entirely eliminated. A further advantage of the long, small diameter motor is the elimination of noticeable gyroscopic effect. The large diameter of the armatures of the overhanging motors introduced 35 a very noticeably gyroscopic effect, especially at high speeds, and this interferes with the shifting of the tool to a new position.

Other and further objects of the present invention will appear as the description proceeds. 40

The accompanying drawing shows, for purposes of illustrating the present invention, one of the many embodiments in which the invention may take form, it being understood that the drawing is illustrative of the invention rather than limiting the same. In the drawing:

Figure 1 is a perspective view illustrating the use of the motorized tool unit held in the hand;

Figure 2 is a longitudinal sectional view through the rear end of the motor and taken on 50 the line 2—2 of Fig. 4;

Figure 3 is a longitudinal sectional view through a hand piece connected to the motor;

Figure 4 is an elevational view of the end cap for the motor; and

Figure 5 is a section on the line 5—5 of Figure 3.

The motorized tool unit utilizes a motor A and a hand piece or tool holder B. A tool, such as a 5 grindstone is shown at C. The entire unit is held in the hand after the fashion of a pencil, the thumb and fingertips gripping the sheath of the hand piece and the motor extending rearwardly between the thumb and index finger of the hand, 10 and a short distance beyond the index finger knuckle. The motor may have an overall length of about 4½ inches and an outside diameter of 7/8 of an inch to 1 inch, and weigh complete 4½ to 6 ounces. The hand piece may be about 2½ 15 inches long, and weigh about 2 ounces. The center of gravity of the hand piece is indicated at b and is practically at the gripping point. The center of gravity of the motor unit is indicated at a and is about 2¼ inches to the rear of the 20 joint where these parts are coupled. Hence, the center of gravity of the complete unit is somewhat closer to the coupling or at approximately the point ab. As a result of these factors, the 25 center of gravity of the complete unit is well below (or in front of) the knuckle joint or may be said to be adjacent the second or middle joint of the index finger and the first joint of the thumb, as will be clearly understood.

Figures 2, 3, and 4 illustrate in detail a suitable embodiment of motor and hand piece whereby the advantages of the present arrangement may be had in practice. It will, of course, be understood that these details may be varied and the major objectives above referred to obtained, 30 so long as the length diameter of parts and mass distribution are kept within a proper range.

The motor a has a cup shaped casing 10 preferably made of one piece of insulating material. This casing carries the field structure of the motor and supports the bearing for the armature 40 shaft.

An insulating brush rigging disc 11 extends across the open end of the casing 10. The disc 11 has a reduced portion 12 which telescopically 45 fits into the casing 10 and small screws 13 secure the disc in place. The disc 11 is provided with a tubular bearing member 14 for the adjacent end 15 of the armature shaft. The disc 11 also carries two tubes 16 which constitute 50 brush boxes (only one of these brush boxes appears in the drawing). The brush boxes 16 are threaded as indicated at 17 to fit threaded holes in the disc 11 and are locked in place by threaded rings 18. Each brush box is threaded as indicated at 19 to receive a screw 20. The brush 55 and brush spring are indicated at 21 and 22 respectively.

The disc 11 also carries a pair of conducting pins 23 adapted to act as field connections. Each 60 pin is threaded through a hole 24 in the disc and is locked in place by a nut 25.

The end cap of the motor is indicated at 26. It is also made of insulating material and is cup shaped so as to telescope over the brush rigging disc 11, its end abutting against the end of the casing 10. Two threaded inserts 27—27 are threaded into the end cap. These inserts are tubular as indicated and are split as shown at 65 28. They are spaced the same as the brush boxes 16 and are such a size as to grip the brush boxes 70 when the parts are assembled. A second pair of tubular inserts 29—29 is also carried by the end cap. These inserts are spaced the same as the pins 23 and are split so as to grip them. 75 The current supply wires are brought in by a four

conductor cord 30 and the separate wires, 30a, 30b, 30c, 30d, soldered to the inserts 28 and 29 as indicated. The end cap is drilled as indicated at 32 to receive screws 33 which are threaded into tapped holes in the screws 28 so that the end cap is firmly secured to the disc 11.

The commutator, as indicated at 34, is close to the disc 11 so that the brushes may bear on it.

The front end 10a of the motor casing 10 is reduced as indicated in the drawing and is provided with an internally threaded bore 35 to receive a threaded bushing 36 preferably made of stainless steel. The bushing is shouldered as indicated at 36' to abut against the end of the insulating casing 10a and locking screws 37 secure these two parts together. The metal bushing 36 carries insulating bushing 38 which in turn supports a phosphor-bronze bearing 39 for the front end 40 of the armature shaft. The shaft is drilled from the outer end to receive an insulating insert 41 and this insert is then provided with a non-circular opening 42. The armature shaft 40 has a shoulder 43 which engages with the end of the bearing 39 to take the thrust caused by the brush springs 22. 25

The metal bushing 36 is internally threaded as indicated at 44 to receive the hand piece. The hand piece is shown in detail in Figures 3 and 5. It is provided with a coupling member 50 externally threaded at 51 to cooperate with threads 30 44. The other end of the coupling is threaded as indicated at 52 to cooperate with the threads 53 on a sheath 54. This sheath, at the front, has a tapered bearing indicated at 55 to accommodate the tapered end 56 of a spindle 57. This 35 spindle extends throughout the length of the sheath. The rear end is reduced and flattened as indicated at 58, to fit the non-circular opening 42. Any other suitable form of driving connection may be used. 40

The spindle is made in two parts, these parts being threaded together as indicated at 60. The left or front part is drilled to accommodate a tool clutch 61 of usual construction, and this tool clutch is adapted to be operated by a two part 45 plunger 62, these parts being threaded together as indicated at 63. The left part of the plunger is provided with a slot 64 to permit adjusting the plunger parts by inserting a screw driver through the clutch. The plunger is prevented from rotating by a pin 63' which is guided in a slot 66 in the inner end of the spindle. The plunger 62 is operated by a lever 67 pivoted at 68 and under the control of a sliding ring 69 carrying a cam 70 cooperative with the serrated edge 55 71 of the lever 67.

The sliding sleeve 69 moves back and forth on the outside of the spindle and is prevented from rotating by the cam 70 secured to it and entering a transverse slot 67' in the spindle part, 60 this slot being made to accommodate the lever 67. The sleeve is moved back and forth by a slider 72 which has a projection 73 adapted to enter an annular recess 74 in the sleeve 69.

The slider 72 is held in place by a stationary 65 outer covering for the sheath. This outer covering comprises two parts 75 and 76, each of which is made up of an outer ring 75' and an inner incomplete ring 75'' open at 75''' to accommodate the slider 72. The ring member 76 is similar to the one 75, except that it is longer and is provided with a slot 76' to accommodate the thumb piece 77 secured to the slider 72. Reciprocating this thumb piece 77 back and forth will actuate 70 75

the clutch in an obvious manner to secure the tool in place or to release it.

The inward thrust of the tool and spindle is taken up by the left or inner end of the spindle which engages with an adjustable bushing 80 carried in threads in the inside of the coupling member 50. This bushing may be adjusted accurately and locked in place by a lock ring 81 indicated in Figure 3. In this manner it is possible to design and provide a hand piece of short, compact nature suitable for use with a short motor or for use with other forms of dental engine. The two part plunger 62 may be adjusted to take up the wear in the clutch and the bearing 80 may be adjusted to take up wear between the spindle and the sleeve or sheath.

The organization which has been described may be handled very easily by the surgeon or dentist. The entire device is so light as not to tire the operator. The operator can actuate the clutch release 71 by the finger or thumb without using the other hand. A tool can be released in this same manner and another tool picked up from a support without necessarily touching the tool to insert the shank of the tool into the hand piece. This organization also has the advantage over many forms of hand piece which require the extending of the hand piece to lengthen it when the tool is clutched.

Owing to the small diameter of the motor armature, there is no noticeable gyroscopic effect even at high speeds, and owing to the small diameter of the motor, there is nothing to obstruct vision such as is the case with large overhanging motors.

This application is a continuation, in part, of application filed March 19, 1930, Serial No. 437,154.

It is obvious that the invention may be embodied in many forms and constructions and I wish it to be known that the particular form shown is but one of the many forms. Various modifications and changes being possible, I do not otherwise limit myself in any way with respect thereto.

What is claimed is:

1. An electric engine comprising a direct connected electric motor and hand piece in axial alignment, the front end of the engine being adapted to be gripped between the thumb and first and second fingers of the hand with the hand piece extending forwardly of the tip of the thumb and fingers and the motor extending rearwardly over the thumb-index finger interdigital space and a short distance beyond the knuckle of the index finger, whereby the engine may be held in the hand after the fashion of a pencil, the hand piece being short and compact so that its rear end is adjacent the gripping point and having a stationary sheath, a rotatable shaft and a releasable clutch to secure a tool to the shaft, the electric motor having a small diameter cylindrical casing rigidly secured to the hand piece sheath and an armature shaft drivingly connected with the hand piece shaft, the mass of the motor being distributed throughout the length of the same, the diameter of the casing being such that the casing substantially fills the space between the index finger knuckle joint and the thumb knuckle joint so as to reduce its range of movement when the tool is applied to the work, the center of gravity of the combined motor and hand piece being in the forward end of the motor so as to fall in front of the first index finger knuckle joint, whereby the engine rests against the thumb-index finger interdigital space without tendency to overturn.

2. An engine as claimed in claim 1, wherein the releasable clutch of the hand piece has an operating member disposed adjacent the rear end of the hand piece for manipulation by the thumb or finger while the engine is held in the hand as set forth.

3. An engine as claimed in claim 1, characterized in that the hand piece is of the same length when clutched to a tool as when released so that the position of the center of gravity of the organization is not altered sensibly by the addition of the tool.

HOWARD A. WHITESIDE. 45
